FLEXIBLE WRIST WATCH BAND
AND THE LIKE

Lee Rappaport, New York, N. Y.

Application March 4, 1949, Serial No. 79,595

2 Claims. (Cl. 224—4)

1

This invention relates to flexible band or strap structures for wrist watches and similar jewelry items.

It is a main object of the invention to provide means affording inexpensive manufacture of wrist watch and like straps which are readily adaptable to and may be employed for retaining and anchoring thereon various sizes and lengths of wrist watches.

Yet a further object of the invention is to provide means affording adjustability of watch anchoring means with respect to the strap structure which is provided with slits through which said anchoring means may be threaded and in which said anchoring means may be swung or otherwise moved.

It is another object of the invention to provide means facilitating in a wrist watch strap structure prevention of pressure on the bars of the wrist watches.

It is a further object of the present invention to provide means rendering possible the connection of the wrist watch with the strap substantially without the employment of tools, stitches and other securing means which are found in conventional straps or bands.

It is still another object of the present invention to provide means ensuring a firm support of the wrist watch or similar article on the strap and ready mounting of the wrist watch thereon, thus permitting easy interchangeability of wrist watches with respect to straps without modifying or in any substantial way changing the attachment or securing means of the strap.

The wrist watch strap according to this invention is characterized in particular by the provision of a plurality of slits extending in the strap and in lengthwise direction thereof, said slits being of predetermined length to permit anchoring means for the wrist watch to move lengthwise of said strap in said slits and to swing relatively to the latter, whereby predetermined lengths of wrist watches may be securely held on said strap and without risking any displacement of the wrist watch during wear.

With the above and other objects in view, the invention will be hereinafter more fully described and the combination and arrangement of parts will be shown in the accompanying drawing and pointed out in the claims which form part of the specification.

In the drawing:

Fig. 1 is a top plan view of the wrist watch strap made in accordance with this invention, together with a wrist watch shown in dot-dash lines;

2

Fig. 2 is a sectional view taken along line 2—2 of Fig. 1, with the wrist watch seen in dot-dash lines;

Fig. 3 is a sectional view similar to that of Fig. 2, with the anchoring means shown in a different position and connected to a wrist watch of a length different from that shown in Fig. 2;

Fig. 4 is a sectional view similar to that of Fig. 2, with the anchoring means in a still different position than those of Figs. 2 and 3 and illustrating a wrist watch of a length different from those shown in Figs. 2 and 3;

Fig. 5 is a sectional view taken along line 5—5 of Fig. 2;

Fig. 6 shows part of a wrist watch strap with anchoring means for a different type of wrist watch than that shown in Fig. 1.

Referring now particularly to Figs. 1 to 5, 10 represents a watch strap which is formed of a bottom layer 11 and a top layer 12. These layers are widened at the median portion or location 13 at which the watch is to be fastened. The strap layers 11, 12 are stitched at different locations to hold the layers together and to thus provide a composite or lined strap. One end of the strap contains a buckle 14 and loops 15 spaced from the buckle. The other end of the strap is adapted to pass through the buckle and the loops and has openings 16 for receiving tongue 17 forming a part of said buckle 14.

Stitching on one side of the location 13 is directed transversely of the strap as indicated at 18. A similar stitching is made on the strap parallel to the stitching or seams 18 as indicated at 19. This permits the upper layer portion between these stitchings to be free for the fixing thereto of anchoring means indicated generally at 20. A similar arrangement of stitching is provided at the opposite sides of the widened portion 13 in order that two such anchoring means can be provided for the connection thereto of a watch 21 which as shown in dot and dash lines may be wider than the strap portion 13. Other portions of the stitching run longitudinally of the strap in order to firmly secure the layers of the strap together.

At the location where the anchoring means are to be placed the upper layer of the strap is provided with two lengthy slits 22, 23 transversely spaced from one another and substantially parallel to the opposite longitudinal edges of the median portion 13.

The anchoring means 20 includes a clamp member 24 having spaced hooked-shaped clamp portions 25, 26 and 27 adapted to receive and re-

tain a pin 28 which may form part of the casing of the watch 21 and which is shaped to coact with the portions 25, 26 and 27 in a hinge-like manner to couple the watch thereto.

Member 24 is secured to the upper strap layer 12 by the extension of a securing pin or element 29 through the retaining means including the slit arrangement 22-23 which pin or element has reduced ends 31 and 32 which pass through openings in depending end plate portions 33 and 34, respectively, forming parts of the member 24 (Fig. 5). Outer strap portions or loops 35 and 36 positioned adjacent and beyond the slits 22, 23 are elevated to conform to the ends of the pin or element 29 while portion 37 lying intermediate said slits forms a support for the middle part of pin 29. By having the slits 22 and 23 of sufficient length, the strap and the anchoring means can be adapted for different lengths of watch casings. These anchoring means can be swung or tilted in the manner as shown in Fig. 2, to receive one size of a watch casing, as indicated at 21' with the pins 29 positioned at locations intermediate the length of the slits while the members 24 are inclined outwardly and upwardly. A second size watch casing 21'' which is longer than the watch casing shown in Fig. 2 can be disposed upon the strap 10 by the members 24 which are moved to extend toward the outer ends of the median strap portion as far as possible and away from median portion 13. To this end, members 24 are tilted outwardly to assume a position seen in Fig. 3. Such an arrangement permits ready accommodation of a long watch casing 21''.

In Fig. 4 a watch casing 21''' which is of short length can be connected over the strap portion 13 by locating members 24 to assume a position shown in Fig. 4 with the attaching pins 29 brought to the innermost ends of the slits 22, 23 and toward the watch strap portion 13. It will also be apparent that watches of still different sizes can be located upon the strap depending upon the tilt of the members and upon the location of the pins 29 connecting the members 24 under portions 35 and 36 of the upper layer. The slits can be made of any desired length providing they are kept within the spacing of the stitchings 18 and 19 so as to provide a wider range of adjustment or for a less range of adjustment.

The clamping portions 25, 26 and 27 may be of any desired length and arrangement. It should also be apparent that a construction could be provided utilizing only the top layer of the strap and the layer 11 can be left off.

In Fig. 6, a slightly different construction is shown. In this arrangement, the watch, as indicated at 41, is of substantially the same width as the strap. The member 24 is the same and is attached by its end portions 33 and 34 and pin 29 to the strap by the extension of the pin 29 through the slits 22 and 23. The watch, however, is connected by a short pin 42 to the central clamp portion 26 of the clamp member 24. This short pin has reduced diameter end portions 43 to which watch projections 44 are connected. By having the reduced end portions of the pin 42, small watch projections 44 may be employed. The members 24, however, are adjustable within the slits in the same manner as above described so that either a smaller length watch or a longer length watch can be applied to the same strap. The watch, however, is of substantially the same width as the strap.

It should be apparent that there has been provided by these constructions, a watch strap which

affords adjustability of the anchoring means with respect to the strap structure either in a pivotal manner or by an actual adjustment of the connecting pin for the anchoring means along the slits. With a construction of this kind, the pressure upon the attaching pins or bars of the wrist watches are kept to a minimum and there is less loss of breakage or the disconnection of the watch from the strap. It will be further seen that it is easy to effect the change of the wrist watches upon the strap, that the strap is adapted for any number of different sizes of wrist watches and without having to reform or reconstruct the attaching structure either upon the watch or upon the strap.

While various changes may be made in the detail construction, it shall be understood that such changes shall be within the spirit and scope of the present invention as defined by the appended claims.

Having thus described the invention, what is claimed as new and desired to be secured by Letters Patent, is:

1. In a strap with a plurality of superposed plies having a seat for a watch casing intermediate the ends and on one surface of the upper ply of said strap; retaining means adjacent two opposite ends of said seat and extending substantially above said seat, each of said retaining means being constituted by two spaced seams extending transversely of said strap surface and joining said plies and two substantially parallel spaced slits located on and passing only through the upper ply provided with said one surface portions of said upper ply positioned intermediate said slits constituting respective complementary parts of loop means positioned intermediate said seams, a pin mounted within and extending through each of said loop means and slideable in said latter in transverse direction of and in linear direction to said one surface of said upper ply, two members each pivotally connected for angular displacement at opposed ends to a respective pin and laterally of said loop means, and hook-shaped clamp means on said members, respectively, and extending from said opposite ends of said pins above said one surface, said clamp means being pivotally engageable with a portion of said watch casing, whereby said watch casing may pivot about said clamp means and relative to said pins, which latter are displaceable angularly and linearly relatively to each other and to the surface of said strap.

2. A strap constructed according to claim 1, wherein said hook-shaped clamp means face each other.

LÉON RAPPAPORT.
